United States Patent Office

Des. 215,358
Patented Sept. 23, 1969

215,358

FILM CARTRIDGE OR SIMILAR ARTICLE

Frederick G. Knowles and Elmer O. Wangerin, Rochester,
N.Y., assignors to Eastman Kodak Company, Rochester,
N.Y., a corporation of New Jersey

Filed May 20, 1968, Ser. No. 12,014

Term of patent 14 years

Int. Cl. D16—99

U.S. Cl. D61—1

FIG. 1

FIG. 2

FIG. 3

FIG. 4

FIG. 1 is a plan view of a film cartridge or similar article of our design;

FIG. 2 is an elevational view taken from the top of FIG. 1;

FIG. 3 is a perspective view showing the top portion of the film cartridge shown in FIGS. 1 and 2; and

FIG. 4 is a perspective view showing the bottom portion of the film cartridge shown in FIG. 3.

We claim:

The ornamental design for a film cartridge or similar article, substantially as shown.
